(Cl. D18—2)

FIG. 1.

FIG. 2.

To all whom it may concern:

Be it known that I, Paul Erney, a citizen of the United States of America, residing at Riverdale, in the county of Bronx and State of New York, have invented a new, original, and ornamental Design for an Acoustical Building Panel, of which the following is a specification, reference being had to the accompanying drawing, forming part thereof.

In the drawing:

Fig. 1 is a plan view of an acoustical building panel

showing my new design and Fig. 2 is a fragmentary view of a tile forming a component part of the panel. The latter is of substantially uniform thickness throughout.

I claim:

The ornamental design for an acoustical building panel, substantially as shown and described.
